UNITED STATES PATENT OFFICE.

LESLIE E. SUNDERLAND, OF JOLIET, ILLINOIS.

MACHINE FOR MAKING BARBED WIRE.

SPECIFICATION forming part of Letters Patent No. 298,538, dated February 12, 1884.

Application filed October 30, 1883. (No model.)

To all whom it may concern:

Be it known that I, LESLIE E. SUNDERLAND, a citizen of the United States of America, residing at Joliet, in the county of Will and State 5 of Illinois, have invented certain new and useful Improvements in Machines for Making Barbed Wire, of which the following is a specification, reference being had therein to the accompanying drawings.

Figure 1 is a side elevation; Fig. 2, a plan view on the top; Fig. 3, a side view of the coiling-shaft and a front view of the cam-wheel that intermittently rotates it; Fig. 4, a cross-section on line 4 of Fig. 3; Fig. 5, a cross-section on lines 1 and 3 of Figs. 1 and 2, showing the barb-wire feed; Fig. 6, a side view of the drive-pulley; Fig. 7, a vertical section of a portion of Fig. 2 on line 2, looking in the direction of the arrow; Fig. 8, a rear view of the 10 reciprocating head *c*, which feeds the strand-wire *W* in the machine; Fig. 9, a side view of the spool-clutch *S⁶* and cross-section of the hollow shaft *S³*, to which it is attached; Fig. 10, a cross-section of the stem *H⁶*; Fig. 11, through 15 which the strand-wire is conducted through the coiler; Fig. 11, a side view of the coiling-shaft detached from the machine; Fig. 12, a perspective view of a finished barb, being the product of the machine; and Fig. 13, a side 20 view of the coiling-shaft set in its boxes and having its reciprocating lever attached.

This machine is for the purpose of manufacturing barbed wire for fencing purposes, such as is shown in Fig. 12, formed of a single 25 strand-wire having crimps at suitable intervals along its length, and having short pieces of wire, pointed at each end, coiled on the said crimps for barbs, as shown in said figure.

For the construction and operation of said 30 machine, reference is had to the accompanying drawings, in which a general side elevation is shown in Fig. 1 and a plan view on the top shown in Fig. 2, and the other figures illustrate different parts and views of said figures to render them more readily understood.

The working parts of the machine are supported on the main frame *A*, which stands on the legs *A'*. A centrally-located cross-shaft, *S*, (shown particularly in Fig. 2,) bears the main 35 drive-pulley *B²* on its outer end, to which the

power is applied, and has attached to it all the cams and cranks that drive the various parts of the machine. A sprocket-wheel, *d'*, is attached to the opposite end of said shaft *S*, and by means of the sprocket-chain *d²* drives the 55 sprocket-wheel *d³* on the hollow shaft *S²*, upon which the spool *W⁴* is placed to spool the finished barbed wire.

Through the hollow shaft *S²* passes the square shaft *S'* through a square opening at the sprocket-wheel end, so that the said square shaft will rotate said hollow shaft, and at the same time permit it to slide along back and forth on said square shaft, to carry the spool back and forth so the barbed wire will be distributed evenly 60 over its surface. The sprocket-wheel *h* on shaft *S* drives sprocket-wheel *h'* on shaft *a⁴* by means of the sprocket-chain *h²*, to drive the wheel *a*, that rotates intermittently the coiling-head *H³* by means of its meshing with the pinion *m* on 65 the part of coiling-shaft marked *F²*, as shown in Fig. 11. The crank *P* on shaft *S* is connected by the pitman *P'* to the sliding head *K*, (shown more particularly in Fig. 7,) to reciprocate the feed-jaws *c* and *c'*, that grasp 70 the strand-wire *W* between the dies *o* and *o'* and feed it forward into the machine, and at the same time crimp the wire between said dies in the form shown in Fig. 12. The waved cam-wheel *H⁷* on the shaft *S* operates the die 75 *Z'*, which, in connection with the stationary die *Z*, cuts off the barbing-wire as it is fed in between said dies, as shown in Fig. 5. The die *Z'* is set in the head *H*, which is pivoted in the frame *H²* by the bolt *v²*, and which head 80 *H* terminates in the tail-piece *H'*, having at its outer end, on the under side, a pair of wrist-pins and friction-rollers, (shown by the dotted lines in Fig. 2,) between which the waved cam *H'* rotates to vibrate said tail-piece horizontally to operate said die *Z'*. The cam *D'* on shaft *S* operates the feed device that feeds the 85 barb-wire *t* into the machine. This feed device is shown more particularly in Fig. 5, it being a cross-section on line 3 of Fig. 2, looking in the direction of the arrow. The waved cam *D'* rotates between the wrist-rollers *D⁴*. (Shown in Fig. 2 and by the dotted lines in Fig. 5.) Looking at Fig. 5, this feed consists of the vertical arms *D''* and *D⁶*, which stand 90

pivoted at the foot in the hanger D⁶. These two arms are connected at the top by means of the link D² and bent lever D', having the set-screw n⁴ in its outer end. The arm D⁵ has 5 its upper end terminate in an elbow to sustain the upper set-screw, n⁵, directly over set-screw n⁴, between which set-screws the barb-wire t passes and is grasped to be fed forward. As cam D' rotates between the wrist-rollers D', 10 the upper end of arm D⁵ oscillates backward and forward, and by its connection with arm D" oscillates that in the same manner. As they move forward toward the machine, they cause the two set-screw dies n⁴ n⁵ to grasp the 15 wire t and drive it forward. The set-screw n³ passes loosely through an opening through arm D" and then screws into the lower side of lever D'. When arm D⁵ moves backward, it will carry with it arm D" as soon as the head 20 of set-screw n³ comes up in contact with arm D". When set-screw n³ is screwed out to its full length, arm D⁵ will move some distance before it will move arm D", and then move it only a short distance, and consequently shorten the 25 stroke of said arm D" and the feed-dies n⁴ n⁵. A longer stroke and feed will be obtained by turning set-screw n³ in, the length of the stroke of the feed being thus regulated by turning said set-screw in or out. The wire 30 thus fed in forms the barb. The wire is prevented from being withdrawn by means of the spring-dog r', pivoted at the side of the frame r and held to its work by the spring r². The upper end of frame r overhangs the dog r', so 35 the wire can pass between said dog and said overhanging portion, as shown in Fig. 5. The sprocket-chain d² drives the spool-shaft S', which is a square rod that passes through a square opening through the length of the 40 shaft S², which rotates in boxes in the frame A³.

When it is desired to place a spool, W⁴, on the shaft S³, the shaft S' is withdrawn, and then passed back through the shaft S² and the spool W⁴, as shown in Fig. 2. The sprocket-chain 45 d² travels or rotates continuously and drives continuously the sprocket-wheel d³ on shaft S², on which it loosely rotates. The spool can only rotate intermittently to wind on it the finished wire, as the strand-wire must stop 50 an instant each time a barb is placed on it, and for that reason the spool must stop long enough to permit the barb to be placed on, and then rotate sufficiently to take up the wire until it is necessary to stop it to place 55 another barb on it. In order to accomplish this, the sprocket-wheel d³ on shaft S² is placed between two friction plates or disks, g and g', the disk g being keyed to the shaft S², so that when it rotates it will rotate the said 60 shaft with it. The outer end of shaft S² is threaded, and a nut, g², having arms by means of which it can be turned, is placed thereon, and between said nut and disk g' is placed a rubber collar, g², and washer g⁴, so that when 65 the nut g² is turned up against said rubber collar it will cause the two disks g and g' to clamp

the sprocket-wheel between them; and clamp it with sufficient force so it will by frictional contact rotate with them. Disk g being keyed to S², rotates that with it, and also the square 70 spool-shaft S', upon which the spool is placed. The frictional contact of the disks g and g' is not so great but that the barbing part of the machine may hold the strand-wire still an instant to place on the barb; but it is intended 75 the strand-wire will only pass through the machine intermittently as fed in by the reciprocating feed c and c', and that the friction on the sprocket-wheel d³ will not overcome the tension on the said strand-wire at the opposite 80 end of the machine, where it passes between the straightening-jaws c¹⁰ c¹², so that by this means the spool may rotate intermittently to take up the finished wire. The spool must be conveyed on shaft S' and right-and-left 85 screw S⁴ back and forth, to distribute the wire over its surface evenly. To accomplish this it is placed on a short hollow shaft, S³, which has a square hole at one end to sleeve on shaft S'. The right-and-left screw-shaft S⁴ has its 90 outer end firmly fixed in the frame A³, and extends forward so its inner end meets shaft S' within the sleeved shaft S³. This shaft S³ has a head, S⁵, integral therewith, with flanges, 95 between which one of the arms of the spool lies, and is held therein by a latch, S⁷. (Shown in Fig. 9.) A switch, S⁵, attached to said head S⁵, runs in the screw S⁴ and causes the spool to traverse said screw-shaft back and forth, for the purpose stated. 100

The operation of the machine is substantially as follows: The strand-wire W enters the machine at the left, looking at Figs. 1 and 2, and travels forward in the direction of the arrow. It first passes between a pair of die-plates, c¹⁰ c¹², between which it draws to give tension to the wire as it is drawn through, and also to straighten out any kinks or bends there may be in it. The upper die-plate, c¹⁰, is set in the arm y, pivoted at its inner end on the 110 frame c, which is partially supported by the brace c¹, while its outer end is held down by the coil-spring y', so as to cause the die-plate c¹⁰ to press firmly on the strand-wire. The spring y' may be adjusted by means of the sliding plate y² to give more or less tension on the arm y. A weight, instead of said spring, would answer the purpose as well. The wire W next 115 passes into the feed, (shown more particularly in Fig. 7,) consisting of the reciprocating head c and bell-crank jaw c', furnished with a pair of dies, o and o', regulated by the set-screws c² c³, and having their meeting faces formed so that when they grasp the wire they will form a bend or crimp in it, such as is shown in 120 Fig. 12. This reciprocating head is driven by the crank P' and pitman P and traverses in the ways c⁶ c⁶. (Shown in Fig. 8.) The head c is divided, as shown in its rear in Fig. 8, so the bell-crank jaw c' can be pivoted between 125 its two parts, as shown, and its lower end hang down so as to be between the set-screw 130

Z^3 and the stop Z^4 made adjustable by the set-screw Z^5 . The stop Z^4 and set-screw Z^5 are attached to a head, K , which reciprocates in ways within said reciprocating head c , and to which head the pitman P is attached, as shown in Fig. 7. When the pitman moves the head forward, it will cause the stop Z^4 to press against the lower end of the bell-crank jaw c' and by that means move the sliding head c forward. A reverse motion causes the set-screw Z^5 to come in contact with said jaw, and thus move the head c backward. The set-screws Z^3 and Z^5 regulate the distance the head c is to reciprocate, and thus regulate the distance apart the barbs are to be placed. A forward movement of the reciprocating head c causes the wire W to be grasped between the dies o and o' and crimped and carried forward into the stem H^6 , which is provided with a channel its entire length, to conduct the wire and hold the crimp right side up or vertical at the place where the barb is placed on. This stem H^6 is shown in cross-section in Fig. 10, and extends entirely through the coiling-shaft H^3 , of which Fig. 11 is an enlarged side view, and is also shown in Figs. 3 and 4. The part F^2 is the part upon which the pinion m , Fig. 3, is firmly keyed. The remaining portion between said pinion and the enlarged head end H^3 is enclosed within a box, R , and is jointed together, as shown in Fig. 11, so the large end H^3 may be reciprocated horizontally by means of the saddle a^8 , pivoted to the ears H^4 on the opposite side of the annular ring H^5 , that lies and turns in a corresponding annular channel in the coiling-head H^3 . This saddle attaches to the lower end of lever a^1 , pivoted near its center in the frame of the machine, while its upper end is provided with a roller-wrist that runs in the cam-channel a^3 of cam a , as shown in Fig. 3. This arrangement will give a reciprocating motion to the part F of said coiling-shaft, and the head part H^3 , having the coiling-hook v on its outer end, so that when the coiling-hook v begins to coil the barb on the strand-wire it will coil as it recedes, and thus give a long coil to the barb to make it cover the entire crimp in the strand-wire, as shown in Figs. 3, 11, and 12, instead of coiling it all on in one place, as it would do if the coiling-pinion did not reciprocate. The stem H^6 , as before stated, passes through the whole length of the coiling-shaft, and is held stationary in the box a^9 , as shown in Figs. 2 and 3, so it will not rotate or get out of place, and thus form a stationary permanent conductor of the wire W up to the coiling-hook v . The coiling-head H^3 rotates in one direction intermittently, and only rotates when a barb is to be coiled on. Each feed of the strand-wire delivers a part of the strand-wire W , where it is crimped directly under the coiling-hook v , as shown in Figs. 3 and 11, and at the same instant the barb-wire t is fed in far enough by the barb-feed (described and shown in Fig. 5) to make a single barb, and at the outer end of the crimp in the

strand-wire from the coiling-hook v . The coiling-head H^3 and the shaft it is attached to then begin to rotate by means of the teeth m' on the pinion m running in the cam-channels a^2 70 on the face of the cam-wheel a , which causes the coiling-hook v to catch the fed-in end of the barb and coil it on the strand-wire W on one of its crimps in the form shown in Fig. 12. The coiling-shaft then stops its rotation by 75 means of one of the teeth of the pinion m having run into the groove a' on the face of the said cam-wheel. As soon as the coiling on of the barb is finished, a wave in cam-wheel H^7 moves the tail-piece H^8 and head H , containing the cutting-off die Z' , Fig. 5, and cuts off the barb from the barb-wire in a diagonal direction, to leave sharp ends for prods. When the head c and jaw c' move forward, the spool takes up as much finished wire as is so fed forward by the said head c and jaw c' . While the barb is being so coiled on the strand-wire, the reciprocating head c returns to perform another like operation. After a barb has thus been placed on the strand-wire, it passes under 85 a press to cause the prods of the barb to point in the proper direction and to straighten them. This press is shown in Figs. 1 and 7, and consists of the arm B , pivoted at B^6 to the standard H^2 , while its other downwardly-extending 90 end is provided with a roller-wrist, to run in the cam-channel of cam-wheel B^7 . The arm B is furnished with the adjustable die R^2 , regulated vertically by the set-screw B . The form of the cam-channel in cam-wheel B^7 will cause 95 die R^2 to descend on a barb just at the time it passes under the said die to perform said service. B' is a bed-plate, over which the wire W passes, and between which and said die R^2 the 100 barb is so pressed. When it ascends, it permits the barb to pass on. The finished barbed wire then passes onto the spool W^4 , over the shoe guide W^2 , which is attached to the outer end of the spring-arm W^3 , which is for the purpose of preventing a sudden jerk or jar to the spool. As the friction plates or disks heretofore described rotate the spool, it draws down on the spring-arm W^3 , which will give a strain to the wire W , and, as said wire is fed forward, 105 said spring will ease the starting of the spool. The barbing-wire t , after it leaves jaws n^5 and n^6 , Fig. 5, passes into the tube t' , which guides the wire into the cutting-off dies Z and Z' . The reciprocating head c is provided with a roller, 110 o^2 , immediately in front of the dies o and o' , over which the strand-wire passes, so as to hold it up and not let it drop when jaw c' opens. The head c' is stopped in its forward movement by the stop c^5 , which is intended to 115 arrest the further movement forward by its engaging with spring c^4 . (Shown in Fig. 1.) The coiling-shaft H^3 may have two boxes instead of one, and constructed as shown in Fig. 13, if desired. The drive-pulley B^2 is loose on 120 shaft S , while the inner expandable rim, B^3 , is integral with the hub b^7 , which sleeves on 125

over shaft S, and is firmly keyed thereto. The collars b, b⁴, and b⁵ are sleeved on said hub loosely. Collar b⁴ has an outwardly-extending arm, b¹⁰, which pivots, by means of the stand-
5 ard b¹², to the frame A, so it cannot rotate with said hub. The arm b' is hinged between the meeting ends of the expandable rim B³ by means of the ears b² b³, Fig. 6, and its lower end is saddled over the collar b, so it will stand
10 in steps on its sides. Collar b⁵ has a lever attached to it, b⁶, so it can be rotated partially on said hub b¹. Collars b⁴ and b⁵ are provided on their meeting faces with radial vertical offsets, as shown in Fig. 2, so that when collar b⁵
15 is partially rotated, it will press collar b⁴ over against collar b, the effect of which is to press upwardly on arm b', and thus expand the rim B³, so that it will have frictional contact with the inner side of the rim of pulley B²,
20 and by such contact be driven or rotated by pulley B², and with it the main shaft S, that drives the machine.

In order to operate the barbing part of this machine, it is absolutely necessary that a spooling device should be used in connection with it to take up the finished barbed wire and draw the strand-wires in and through the machine. For that reason a spooling device is shown and described; but any other suitable
25 30 spooling apparatus may be used as well as the one shown.

Having thus described my invention, what I claim as new, and desire to secure by Letters Patent, is as follows, to wit:

- 35 1. In a wire-barbing machine, the combination of the shaft S, crank P', pitman P, reciprocating head K, having the adjustable stop Z⁴ and set-screws Z³ Z⁵, reciprocating head c, having the bell-crank jaw c', crimping-dies o o', set-screws c² c³, and supporting-roller o², straightening-plates c¹⁰ c¹², stem H⁶, and coiling-shaft H³, having the coiling-hook v, and adapted to reciprocate and rotate, as and for the purpose set forth.
- 40 45 2. In a wire-barbing machine, the combination of the shaft S, sprocket-wheel h, sprocket-chain h², sprocket-wheel h', shaft a⁴, cam-wheel a, having the cam-channels a a² a³, lever a⁷, having the roller-wrist n', saddle a⁸, annular
50 ring H⁵, having the two ears or pins H⁴, coiling-shaft H³, having the coiling-hook v, and

adapted to reciprocate and rotate its coiling end simultaneously, pinion m, and stem H⁶, as and for the purpose set forth.

3. In a wire-barbing machine, the combination of shaft S, waved cam-wheel D⁷, wrist-rollers D⁴ D⁴, arms D⁵ and D⁶, hanger D⁶, link D², lever D', set-screw dies n⁴ n⁵, set-screw n³, dog r', spring r², standard r, and guide-tube t², as and for the purpose set forth. 60

4. In the wire-barbing machine described, the combination of the shaft S, waved cam H⁷, lever H', having the head H, standard H², cutting-off dies Z and Z', set-screws v' and Z², and bed-plate A⁴, as and for the purpose set forth. 65

5. In a wire-barbing machine, the combination of the shaft S, cam-wheel B⁷, arm B⁸, having the roller-wrists to run in the cam-channel of said cam, head B, pivoted to standard H², bed-plate B⁵, die R², and set-screw B', as and for the purpose set forth. 70

6. In a wire-barbing machine, the combination of the cam-wheel a, lever a⁷, saddle-link a⁸, annular ring H⁵, and pinion m, adapted to 75 rotate and reciprocate the coiling end of the coiling-shaft H³ simultaneously, as and for the purpose set forth.

7. In a wire-barbing machine, the combination of the reciprocating head c, dies o and o', 80 and supporting-roller o², as and for the purpose set forth.

8. In the wire-barbing machine described, the combination of the straightening-plates c¹⁰ c¹², strand-wire feed consisting of the reciprocating head c and bell-crank jaw c', and dies o and o', operated by the mechanism described, coiling-shaft H³, having the coiling-hook v, and adapted to reciprocate and rotate its coiling end simultaneously by the mechanism described, cutting-off dies Z Z', and their operating mechanism, barb-wire feed described and illustrated, particularly in Fig. 5, press B, having the die-press R², and operated as described, guide-shoe W', and spring-standard 95 W³, all adapted to operate as and for the purpose set forth. 90
